CLAIM

The ornamental design for a container adaptor ring or the like, substantially as is shown and described.

DESCRIPTION

FIG. 1 is a perspective view of a container adapter ring or the like showing our new design;

FIG. 2 is a top plan view thereof;

FIG. 3 is a bottom plan view thereof;

FIG. 4 is a side elevational view thereof;

FIG. 5 is an enlarged cross-sectional view thereof taken along line 5—5 of FIG. 2.

FIG. 1

↔ 5

FIG. 2

FIG. 3

FIG. 4
